UNITED STATES PATENT OFFICE

159,512

DISPLAY STAND

Anthony Paolillo, Brooklyn, N. Y., assignor to Quest Shon Mark Brassiere Co., Inc., Brooklyn,
N. Y., a corporation of New York

Application December 3, 1948, Serial No. 149,936

Term of patent 3½ years

(Cl. D80—8)

To all whom it may concern:

Be it known that I, Anthony Paolillo, a citizen of the United States, residing at Brooklyn, in the county of Kings and State of New York, have invented a new, original, and ornamental Design for a Display Stand, of which the following is a specification, reference being had to the accompanying drawing, forming part thereof.

I claim:

The ornamental design for a display stand, as shown.

ANTHONY PAOLILLO.
